CLAIM

The ornamental design for a charging dock, as shown and described.

DESCRIPTION

FIG. 1 is a front, top, right perspective view of the charging dock in a first configuration;

FIG. 2 is a rear, bottom, left perspective view of the charging dock in the first configuration;

FIG. 3 is a front elevational view of the charging dock in the first configuration;

FIG. 4 is a rear elevational view of the charging dock in the first configuration;

FIG. 5 is a top plan view of the charging dock in the first configuration;

FIG. 6 is a bottom plan view of the charging dock in the first configuration;

FIG. 7 is a right side elevational view of the charging dock in the first configuration;

FIG. 8 is a left side elevational view of the charging dock in the first configuration; and,

FIG. 9 is a front elevational view of the charging dock in a second configuration.

The broken lines in the drawings are for the purpose of illustrating environmental structure and portions of the article which form no part of the claimed design.

1 Claim, 6 Drawing Sheets
